BRUSH ASSEMBLY

Irvin H. Dunham, Racine, Wis., assignor to Electric Motor Corporation, Racine, Wis., a corporation of Wisconsin

Application December 24, 1934, Serial No. 759,084

4 Claims. (Cl. 172—324)

This invention appertains to electric motors, and more particularly to a novel brush assembly therefor.

In certain lines of the electric motor industry, it is essential that the motors be so constructed that the same can be economically manufactured on a quantity basis and still be of a rugged and durable type capable of withstanding the hard usage of the layman.

10 It is therefore one of the salient objects of my invention to provide novel means for simplifying the brush assembly of electric motors, whereby the same can be cheaply made and readily assembled in the motor casing, and capable of effectively performing its desired office, the construction being such that the brushes can be easily renewed when worn.

Another important object of my invention is the provision of novel and effective means for insuring the proper contact between the brush and its holder or housing on motors both of the high and low amperage type.

A further object of my invention is the provision of novel means for constructing the housing or holder and the contact member of brushes of the "shunt" type, used with current or high amperage, in which not only the proper contact is insured without deterring from the function of the brush spring, but ease in assembling is also obtained.

45 A further object of my invention is the provision of an insulation plate for each brush assembly, with novel means for connecting the one-piece sheet metal brush holder or housing therewith, and with novel means for anchoring or securing the plate to the motor casing, whereby a simple construction is obtained with the desired spacing between the motor casing and the current conducting parts of the brush assembly.

40 A still further object of my invention is the provision of adjustable caps carried by the motor casing, and independent of the brush holder, for securing the desired adjustment of the brush spring and the proper contact between the spring and the housing, the caps allowing the removal of the spring and brush through the casing.

With these and other objects in view, the invention consists in the novel construction, arrangement, and formation of parts, as will be hereinafter more specifically described, claimed, and illustrated in the accompanying drawings, in which drawings:—

50 Figure 1 is an inner end elevation of a part of a motor casing, showing one form of my improved

brush assembly incorporated therewith, parts of one of the brush assemblies being shown broken away and in section to illustrate structural details.

Figure 2 is an enlarged fragmentary section taken substantially on the line 2—2 of Figure 1, looking in the direction of the arrows.

Figure 3 is a detail fragmentary section, taken on the line 3—3 of Figure 1, looking in the direction of the arrows, illustrating the means for anchoring or securing the brush housing or holder to the motor casing.

Figure 4 is a transverse section through the brush assembly taken substantially on the line 4—4 of Figure 2, looking in the direction of the arrows, illustrating the means of anchoring the assembly to the motor casing.

Figure 5 is a detail transverse section taken substantially on the line 5—5 of Figure 2, illustrating the brush spring contact ring.

Figure 6 is a view similar to Figure 1, illustrating another form of brush assembly.

Figure 7 is an enlarged fragmentary sectional view taken substantially on the line 7—7 of Figure 5.

Figure 8 is a detail plan view of the blank from which the brush holder or housing is formed.

Figure 9 is a detail side elevation of the brush holder support.

Figure 10 is a detail side elevation of my novel contact clip.

Figure 11 is a detail plan view of the brush holder base or plate.

Referring to the drawings in detail, wherein similar reference characters designate corresponding parts throughout the several views, the letter C generally indicates one part of a motor casing, and the letter A one form of my improved brush assembly associated therewith.

The motor casing part C includes an annular side wall 15, and an end wall 16, through which extends the armature shaft (not shown) which carries the usual commutator and armature core. The casing part C is detachably associated with the main part (not shown) of the motor casing.

My improved brush assembly A comprises a brush holder base or plate 20 formed of insulation, and the same is provided at spaced points on opposite sides of its longitudinal axis with slots 21, for a purpose which will be later set forth. This plate of insulation is also provided with slots 22 adjacent to the side edges of the plate, and the purpose of these slots will be more fully set forth.

Firmly mounted upon the plate or base 20 is the brush holder or housing 23, which is formed

30

55

from a single blank of sheet metal 24 folded on longitudinal lines 25 to provide spaced, longitudinally extending side walls 26 and an outer connecting wall 27. The side walls 26 have formed thereon bendable tongues 28, which are inserted through the slots 21, and then clinched, as clearly shown in Figure 4 of the drawings. By this arrangement a brush holder or housing is formed open at its opposite ends.

10 To securely anchor the plate or base 20 with the housing 23 to the motor casing part C, I utilize a pair of sheet metal brush holder supports or clips 29. The inner longitudinal edges of the clips 29, or brush holder supports, are each provided with a tongue 30, and these tongues are inserted through the slots 22 and then upset as at 31. The outer edges of the clips are provided with a pair of spaced legs 32, which are inserted through slots 33 formed in the motor casing part 15 C, and after these legs are inserted in place, the same are bent at right angles, as at 34, into intimate contact with the outer face of the motor casing part C. By this arrangement of parts it can be seen that a simple brush holder is provided with exceptionally simple and durable means for anchoring the same to the motor casing with the proper and desired spacing.

In the "shunt" type of brush holder, one longitudinal side wall 26 of the brush housing or holder 23 is provided with a longitudinally extending slot 35, which terminates short of the inner end of the housing. The opposite end of the slot 35 opens out through the outer end of the housing. The housing slidably receives the brush 36, which has firmly anchored to its inner end the wire 37, which wire has in turn anchored thereto the current conducting contact ring 38. The wire 37 slidably extends through the slot 35 so that free, unimpeded sliding movement of the brush 36 is insured. Mounted within the inner end of the brush holder or housing 23 is the expansion current conducting coil spring 39, and this spring bears against the inner end of the brush, and extends through the contact ring 38 into a cap 40 formed of insulation adjustably carried by the annular side wall 15 of the motor part casing C.

In actual practice the cap 40 is threaded into the casing until the same forces the contact ring into intimate engagement with the housing or brush support 28. I lay particular stress on the contact ring 38, as by the use of the same free movement of the spring 39 is insured, and at the same time I am permitted to obtain a positive contact between the ring and the housing or support 28.

Referring more particularly to Figures 6, 7, and 10, it will be seen that I have shown a brush assembly of the low amperage type, and this brush assembly is identical with the brush assembly just described, with the exception that a contact clip 41 is utilized instead of the contact ring 38. In this form I also employ a brush 42, in which the

wire 37 is eliminated, and hence the necessity of the slot 35 is also dispensed with.

Particular attention is invited to the contact clip 41, and it will be noted that the same includes a hollow circular body portion 43, which is detachably fitted within the insulated cap 40. Formed on the hollow head 43 are resilient diverging legs 44. In assembling the brush parts in this form, the expansion brush spring is placed within the brush holder or housing against the brush, and in the hollow head 43, and the legs of the clip are placed on opposite sides of the brush holder or housing in intimate engagement with the side walls thereof. Obviously, upon tightening of the cap the legs will be forced into tighter engagement with the brush holder or housing, thus insuring proper contact between the spring and the housing.

Changes in details may be made without departing from the spirit or scope of this invention, but what I claim as new is:—

1. In an electric motor, a casing, and a brush assembly therefor including a brush holder, the casing having an opening in alignment with the holder, a cap of insulation adjustably threaded in the opening and movable toward and away from the holder, an expansion spring having its opposite ends fitted within the holder and the cap, and a contact clip carried by the cap and receiving the spring having resilient legs movable into intimate contact with the sides of the holder by said cap.

2. In an electric motor, a casing having an opening therein and a brush assembly therefor including a brush holder in alignment with the opening, a brush slidably mounted in said holder, a hollow cap of insulation adjustably threaded into said opening, a contact clip including a hollow head fitted within the cap, and resilient contact legs for engaging the opposite sides of the holder, and an expansion spring fitted within the holder and in the hollow head.

3. As a new article of manufacture, a contact clip for brush assemblies comprising a hollow head and a pair of spaced resilient legs formed on said head and diverging therefrom.

4. In an electric motor, a casing, a brush assembly disposed within the casing, including a plate formed of insulation having a pair of spaced slots on opposite sides of its longitudinal axis, and another pair of slots adjacent to its side edges, a support including a pair of metallic plates having tongues insertable through the slots adjacent to the side edges of the plate and bendable tongues for engaging the motor casing whereby to hold the plate in spaced relation to the motor casing, a one-piece sheet metal housing including side walls and a connecting wall, bendable tongues on the side walls insertable through the first-mentioned slots of the plate, whereby to anchor the housing to the plate, and a brush slidably mounted in the housing on the plate.

IRVIE H. DUNHAM.
